UNITED STATES PATENT OFFICE

162,425

DISPLAY RACK

Louis G. Meyers, New York, N. Y.

Application November 20, 1950, Serial No. 13,062

Term of patent 7 years

(Cl. D80—9)

To all whom it may concern:

Be it known that I, Louis G. Meyers, a citizen of the United States of America, residing at New York city, in the county of New York and State of New York, have invented a new, original, and ornamental Design for a Display Rack, of which the following is a specification, reference being had to the accompanying drawing, forming a part thereof.

In the drawing:

Figure 1 is a front elevational view of a display rack embodying my new design,

Figure 2 is a top plan view thereof,

Figure 3 is a rear elevational view,

Figure 4 is a side elevational view.

I claim:

The ornamental design for a display rack, as shown.

LOUIS G. MEYERS.
